UNITED STATES PATENT OFFICE.

CHARLES WINKELMANN, OF NORTH BERGEN, NEW JERSEY, ASSIGNOR TO THE SINGER MANUFACTURING COMPANY, OF ELIZABETH, NEW JERSEY, A CORPORATION OF NEW JERSEY.

FOLDER FOR CIRCULAR WORK.

Application filed December 2, 1919. Serial No. 341,957.

To all whom it may concern:

Be it known that I, CHARLES WINKELMANN, a citizen of the United States, residing at North Bergen, in the county of Hudson and State of New Jersey, have invented certain new and useful Improvements in Folders for Circular Work, of which the following is a specification, reference being had therein to the accompanying drawings.

10 This invention relates to folders for sewing machines and its principal object is to provide means for folding under the edge of a comparatively small circular piece of cloth and feeding it to the stitching mechanism of 15 a sewing machine so that it is folded and stitched with precision entirely around the circle. It is especially adapted for sewing under the edges of the circular insignia patches used on the sleeves of the uniforms 20 of soldiers, sailors and members of other organizations.

It comprises in its preferred embodiment a supporting or anchoring plate adapted to be adjustably secured on the bed-plate of a 25 sewing machine in operative relation to the stitch-forming mechanism and provided at one end with a scroll section substantially U-shaped in cross section to form a work turning channel open laterally and with a 30 tongue in the shape of a plate with a curved edge extending into this open side but spaced from all sides of the scroll section. On the under side of the tongue-plate but spaced a suitable distance from the curved 35 edge thereof is a finger forming a guide for the free edge of the folded under margin of the material. The tongue-plate is adjustable relative to the scroll section to allow for different thicknesses of material.

40 Referring to the accompanying drawings which illustrate the preferred embodiment of the invention, Fig. 1 is a plan view showing a portion of the bed-plate of the sewing machine and presser-foot with the folder 45 in operative relation thereto. Fig. 2 is a front elevation of the folder in operative position as shown in Fig. 1. Fig. 3 is an end elevation of the same. Fig. 4 is a perspective showing a circular piece of material 50 as it is started in the folder. Fig. 5 is a bottom plan view of the folder. Fig. 6 is a rear elevation of the folder. Figs. 7, 8 and 9 are detailed sectional views on substantially the lines 7-7, 8-8 and 9-9, re-

spectively, of Fig. 5. Fig. 10 is a perspective view of a portion of the throat-plate. Fig. 11 is a section on substantially the line 11-11 of Fig. 10.

The folder is adapted to be used with the usual type of sewing machine comprising a bed-plate 1, head 2, reciprocating needle 3, presser-foot 4, shuttle mechanism 5 and feed mechanism 6. The folder comprises a comparatively heavy base-plate 7 adapted to be adjustably secured to the bed-plate 1 by means of the thumb-screw 8 passing through the slot 9 and screwed into the bed-plate. Formed on the end of the plate 7 is a scroll section 10 which is substantially U-shaped in cross section forming a channel and is placed with the legs extending substantially horizontally with the open side to the left as viewed in Fig. 1. It will be noted from Fig. 5 that the lower leg 11 commences a short distance from the forward edge of plate 7, gradually increases from zero to a maximum a short distance from the rear edge of the plate and then runs out into the end of the plate. The upper leg 12 of the scroll section at the rear of the plate is substantially the same length as the lower leg and about half way the length of the plate 7 lengthens rapidly and curves upwardly and ends on the plate a short distance from the front edge thereof. The longer portion 85 as at 13 has its edge bent upward slightly to facilitate the entrance of the work into the guide. This portion is also bent upwardly as shown in order to give greater clearance to the work.

Adjustably secured to the plate 7 by means of the screw 14 is a tie-plate 15 having mounted thereon at its opposite end portion the tongue plate or internal guide 16. This plate is comparatively thin and preferably has one edge 17 thereof formed on substantially the arc of a circle with its center substantially in line with the portion 18 of the rear edge of the plate so that the rear end of the curve is substantially normal to this portion. It is, however, not necessary that this curve be formed on the arc of a circle but may be any desired curve. The tie-plate 15 is bent downwardly at 19 so that the curved edge 17 may be placed 100 between the legs of the scroll-section as clearly shown in Figs. 6 to 9. By loosening screw 14, plate 15 and with it tongue-plate

16 may be adjusted about the screw 14 as a pivot which will move the rear portion of the curved edge of the plate 16 adjacent the edge 18 nearer to or farther from the inner 5 surface of scroll-section 10. After adjustment the plates 15 and 16 may be clamped in adjusted position by tightening screw 14. Secured to the tie-plate 15 on the under side 10 thereof, is an edge-guide 20 which is formed of a piece of sheet metal with a rectangular section 21 at one end and a narrow finger 22 extending from one edge thereof and bent substantially at right angles thereto as 15 shown in Figs. 5 and 7 to 9. It is secured to the plate 15 by means of a screw 23 extending through the rectangular portion 21 preferably in such a manner that the vertical finger portion 22 extends substantially 20 parallel with the bottom of the U-shaped scroll-section but is spaced away from the curved edge 17 any suitable distance, as desired. The top portion of the finger 22 is bent laterally at 24 to fill in the space formed at the junction of the plates 15 and 25 16 immediately under the forward edge of the upper leg 12 of the scroll-section.

It is desirable that the work after being folded be fed to the needle at substantially the top surface of the throat-plate 25. This 30 throat-plate is therefore formed with a recess or depression 25' as shown in Figs. 10 and 11, into which the finger 22 and the lower leg 11 are adapted to extend to allow the lower rear edges of the plates 7 and 16 35 to be positioned adjacent the top of the throat-plate. This recess or depression is located immediately in front of the needle-opening 26 of the throat-plate. Immediately to the rear of the needle opening 40 is a feed-dog opening 27 through which the feed-dog 28 is adapted to operate. This feed-dog is made with comparatively few teeth so as to readily release the work in that it is not fed straight but comes off the 45 feed-dog in a lateral direction due to its curvature. It will be noted that the presser-foot has one toe removed in order that the attachment may be placed so that as the work leaves the guide the edge thereof is 50 adjacent the path of the needle.

In operation a piece of circular material 29 is placed within the scroll section with the presser-foot 4 and needle 3 raised and is moved laterally until its marginal portion 55 within the scroll section is folded under and the edge thereof contacts with the edge-guide or finger 22 under the plate 16. The operator then presses her finger on substantially the center of the circular piece 29 60 at about C as shown in Fig. 4 which is on the plate 16 and adjacent the rear edge of the latter and starts the machine. The edge of the material comes out the rear end of the scroll-section folded and is immediately 65 stitched adjacent its folded edge and is

drawn through by the feed-dog. The whole piece turns about the end of the operator's finger as a pivot, which, as stated above, is substantially at its center, until the entire circumference is folded and stitched. It 70 will be noted that in this folding operation the U-shaped scroll-section folds the marginal portion of the piece around the curved edge 17 of the plate 16, which particularly 75 facilitates this operation in the folding of curved or circular work. The edge of the material as it passes through the folder abuts against the forward portion 10' of the scroll-section, as shown in Fig. 4, and is 80 gradually folded under the edge 17. In order that the piece should be properly finished it is important that the folded portion be stitched closely adjacent the folded edge thereof and in order to do this it is 85 necessary that the folder be so placed with respect to the needle that the stitching occurs immediately after the work leaves the rear or delivery ends of the scroll-section and the curved edge 17 of the plate 16, as clearly shown in Fig. 1. 90

Having thus set forth the nature of the invention, what I claim herein is—

1. The combination with a sewing machine throat-plate having a needle-hole and a depression in front of said needle-hole, of a folding attachment comprising a plate provided with a scroll-section substantially U-shaped in cross-section and placed on its side in said depression, a guide-plate having a curved edge extending between the legs of the scroll-section and spaced therefrom, and edge-guiding means on the lower side of the guide-plate adjacent the curved edge thereof. 95

2. A folder for sewing machines comprising a plate provided at one end with a scroll-section substantially U-shaped in cross-section placed on its side; the lower leg of the scroll increasing from zero at its front end to a maximum a short distance from its rear end and the upper leg being substantially the same length as the lower section, at its rear end, but increasing to a maximum adjacent its front end, and a guide-plate having a curved edge extending between the legs of the scroll-section and spaced therefrom. 105

3. The combination with a sewing machine having stitch-forming and feeding mechanisms, of a folder comprising a plate provided with a scroll-section substantially U-shaped in cross-section and placed on its side, and a guide-plate having a curved edge extending between the legs of the scroll-section and spaced therefrom, said guide-plate also having a work-supporting surface portion disposed at the side of the sewing point and substantially in a line through the sewing point normal to the direction of feed. 120

4. A folder for sewing machines, comprising a plate provided with a scroll-section 130

- substantially U-shaped in cross-section placed on its side, a guide-plate provided with a curved edge extending between the legs of the scroll-section and spaced therefrom, means for adjustably securing the guide-plate to the first plate and an edge guide extending on the lower side of the guide-plate adjacent the curved edge thereof.
5. A folder for sewing machines having a bed-plate and a throat-plate with a needle opening therein comprising a plate adapted to be adjustably secured to the bed-plate of the machine and provided with a scroll-section substantially U-shaped in cross-section and placed on its side, a guide-plate formed with a curved edge extending between the legs of the scroll-section and spaced therefrom, an edge-guide on the under side of the guide-plate adjacent the curved edge thereof, and means for securing the folder with the rear or delivery ends of the scroll-section and curved guiding edge adjacent the needle opening.
20. 6. A sewing machine having stitching mechanism including a needle, and a hemming device comprising a flat plate having an outwardly arched, circular edge, on which plate fabric is adapted to rest and to be turned with the edge of the fabric extending over said curved edge, and a folder arranged to guide the edge of the fabric around said curved edge whereby the fabric may be turned around on said plate while the edge thereof is folded around the curved edge of said plate said needle being disposed approximately in the line of said circular edge.
25. 7. A sewing machine having stitching mechanism including a needle, and a hemming device comprising a flat plate having an outwardly arched, circular edge terminating adjacent the sewing needle, on which plate fabric is adapted to rest and to be turned with the edge of the fabric extending over said curved edge, and a folder arranged to guide the edge of the fabric around said curved edge whereby the fabric may be turned around on said plate while the edge thereof is folded around the curved edge of said plate.
30. 8. A sewing machine having stitching mechanism including a needle, and a hemming device comprising a flat plate having an outwardly arched, circular edge terminating adjacent the sewing needle, on which plate fabric is adapted to rest and to be turned with the edge of the fabric extending over said curved edge, and a folder arranged to guide the edge of the fabric around said curved edge whereby the fabric may be turned around on said plate while the edge thereof is folded around the curved edge of said plate.
35. 9. A sewing machine having stitching mechanism including a needle, and a hemming device comprising a flat plate having an outwardly arched, circular edge terminating adjacent the sewing needle, on which plate fabric is adapted to rest and to be turned with the edge of the fabric extending over said curved edge, and a folder arranged to guide the edge of the fabric around said curved edge whereby the fabric may be turned around on said plate while the edge thereof is folded around the curved edge of said plate.
40. 10. A sewing machine comprising sewing means and a hemming device, including a fabric plate having a curved edge leading toward the sewing means, a folder adapted to guide the edge of the fabric around and under said curved edge, and a gauge or stop under said plate having an abutting surface crossing the arc of said curved edge.
45. 11. A sewing machine comprising sewing means including a needle and a needle plate having a needle aperture, and a groove in advance of the needle aperture, a plate having a curved edge leading toward said needle aperture, a folder adapted to guide the edge of the fabric around and under said curved edge, said folder extending into the groove in the needle plate, and a gauge or stop for the edge of the fabric arranged below said curved edge and extending into said groove in the needle plate.
50. 12. A sewing machine comprising stitching means including an apertured needle plate, a sewing needle operating in said aperture, said needle plate having an aperture for the feed dog arranged near the needle aperture, a feed dog movable therein, a fabric plate having an outwardly arched curved edge leading toward and terminating just in advance of the needle aperture of the needle plate, on which fabric plate fabric is adapted to rest and to be turned with the edge of the fabric extending over said curved edge, a folder arranged to guide the edge of the fabric around said curved edge, and a presser foot near said needle, having a claw extending inside the arc of the curved edge of said fabric plate.
55. In testimony whereof, I have signed my name to this specification.

CHARLES WINKELMANN.
